AUTOMATIC PRIMER FOR INTERNAL
COMBUSTION ENGINES

John W. Fitz Gerald, Milwaukee, Wis., assignor
to Briggs & Stratton Corporation, Milwaukee,
Wis., a corporation of Delaware

Application March 12, 1934, Serial No. 715,136

6 Claims. (Cl. 123—187.5)

This invention relates to new and useful improvements in automatic primers for internal combustion engines, and has as an object to provide an automatic priming device which is controlled jointly by engine suction and the thermal condition of the engine.

Another object of this invention is to provide a priming device of the character described in which the admission of priming fuel to the engine is controlled by two independent valves, one controlled jointly by engine suction and temperature variations, and the other controlled solely by temperature changes.

A further object of this invention is to provide a priming device of the character described, which is simple in construction and easily applied to any conventional type of internal combustion engine.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is an elevation view showing part of a carburetor and the manifolds of an internal combustion engine, and illustrating the application of this invention thereto;

Figure 2 is a side elevation view of the priming device per se;

Figure 3 is a longitudinal section view through Figure 2 on the plane of the line 3—3;

Figure 4 is a section view taken through Figure 3 on the plane of the line 4—4; and

Figure 5 is a section view similar to Figure 3, but illustrating the valves in different positions.

Referring now more particularly to the accompanying drawings in which like numerals indicate like parts throughout the several views, the numeral 5 designates the carburetor of an internal combustion engine supplied with fuel by a supply line 6 and conducting a combustible mixture to an intake manifold 7 through a riser 8. As is customary, an exhaust manifold 9 is located in juxtaposition to the intake manifold.

The primer, indicated generally by the numeral

10, has an inlet 11 connected to the supply line 6 by a pipe 12 and an outlet 13 connected by a pipe 14 to the intake manifold to afford a direct communication between the supply line and the manifold under certain conditions.

As best shown in Figures 3 and 4, the inlet 11 leads to a transverse bore 15 in the body 16 of the device with which two lateral bores 17 and 18 communicate. Intermediate the length of the body 16, the bores 17 and 18 are counter-bored as at 19 and 20, respectively, to define abrupt shoulders forming valve seats 21 and 22, respectively.

Adjacent the valve seats, both bores 17 and 18 communicate with a cross bore 23, the opposite ends of which are closed by plugs. At a medial point, the bore is connected with the outlet 13 through a bore 24.

The several bores formed in the body provide two separate fuel passages from the inlet 11 to the outlet 13. These passages are independently closed by needle valve members 25 and 26 operating in the bores 19 and 20 for cooperation with the valve seats 21 and 22, respectively.

The valve member 25 is controlled entirely thermostatically. Its outer end projects through a pocket 27 formed as a counterbore to the bore 19, and has a stop flange 28 fixed thereto, between which and the bottom of the pocket 27, a compression spring 29 is confined. The spring 29 yieldably urges the valve member 25 to its open position against the opposition of the spring tension of a bi-metallic U-shaped member 30 having one end anchored to the body 16 as at 31 and its other end bifurcated to engage in an annular groove 32 in a head 33 fixed to the extreme outer end of the stem of the valve member 25.

The disposition of the metals of the thermostatic member 30 is such that when the ambient temperature is cold, the valve member is permitted to be moved to open position by its spring 29, as shown in Figure 3, but as the temperature rises, the thermostat 30 flexes and brings its free end in toward the body 16 to gradually close the valve member 25 against the action of the spring 29.

The stem 37 of the other valve member 26 extends outwardly through a bore 35, which forms a cylinder for a piston 36 secured to the stem. The outer end of the stem 37 is slidable in a hole through a plug 38, which closes the end of the cylinder bore 35. Air bleeds 38' through the plug, permit the piston 36 to respond to suction created within the cylinder bore through its communication with the intake manifold 7.

To insure such communication between the cylinder bore and the manifold, the inner end 39 of the valve stem is polygonal in cross section to at all times afford communication between the cylinder bore 35 and the cross bore 23, which, as hereinbefore noted, is in constant communication with the intake manifold.

The extreme outer end of the valve stem 37 has an annular groove 40 with which the bifurcated end of a second bi-metallic U-shaped strip 41 engages. The opposite end of the strip 41 is anchored to the body 16 by securing means 42.

The spring tension of the thermostatic strip 41 is sufficiently light to permit engine suction 15 acting upon the piston 36 to move the valve member 26 to closed position just as soon as the engine becomes operative, but in the absence of engine suction, and while the ambient temperature is low, the thermostatic strip 41 holds the 20 valve member 26 in open position, as shown in Figure 3.

The operation of the device thus is as follows: Assuming that the engine is cold, and the ambient temperature of the thermostats likewise is 25 low, the valve members 25 and 26 are consequently in open position as illustrated in Figure 3. During the starting of the engine, the suction built up therein is insufficient to move the valve member 26 to closed position, so both valves remain 30 open to admit the maximum volume of auxiliary or priming fuel to the intake manifold.

Just as soon as the engine becomes operative under its own power, the suction builds up to a point sufficient to move the valve member 26 to 35 closed position against the spring tension of the thermostat 41, by its action upon the piston 36. The volume of priming fuel flowing to the intake manifold is thus materially reduced.

The valve member 25, however, does not close 40 at this time, but remains in open position until the temperature of the engine rises sufficiently to flex the thermostatic strip 30 by reason of its proximity to the exhaust manifold, toward the body of the priming device sufficiently to overcome the spring 29 and move the valve member 25 to closed position.

While the valve member 25 is being moved to closed position by its thermostatic strip 30, the thermostatic strip 41 is also being flexed by the 50 temperature rise to force its free end in toward the body 16 of the device so that if after the engine is operating properly and normal operating temperature has been reached, and the effective suction of the engine is momentarily 55 decreased as by suddenly opening the throttle, the valve member 26 will not be moved, being held in closed position by its thermostat 40.

Obviously, when the engine cools off, after being stopped, both valve members will again resume 60 their open positions.

From the foregoing description taken in connection with the accompanying drawings, it will be readily apparent to those skilled in the art to which this invention appertains, that this invention affords a novel and extremely simple, fully automatic priming device for internal combustion engines and that an exceptionally fine and even control of the supply of priming fuel to the engine is had at all times.

70 What I claim as my invention is:

1. In combination with an internal combustion engine, an automatic priming device comprising means providing a plurality of fuel passages connected in parallel for conducting fuel to the engine, valves in said passages for controlling the

admission of fuel to the engine, engine suction responsive means for closing one of said valves, thermostatic means for opposing said engine suction responsive means and operable to hold said valve open when the ambient temperature is low and in the absence of engine suction and to hold the valve closed when the ambient temperature is high even though engine suction ceases, a spring for yieldably opening the other valve, and thermostatic means opposing said spring and tending to close said second designated valve as the ambient temperature rises.

2. In combination with an internal combustion engine, an automatic priming device comprising means providing a plurality of passages connected in parallel and adapted to jointly supply fuel to the engine, valves in said passages for jointly controlling the admission of fuel to the engine, engine suction responsive means for closing one of the valves, temperature actuated means for opposing the suction responsive means and for holding said valve open until a predetermined degree of engine suction has been reached, said temperature actuated means also holding said valve closed when a temperature of a predetermined high degree has been reached regardless of variations in engine suction, and a second temperature actuated means for controlling the other valve.

3. In combination with an internal combustion engine, an automatic priming device comprising a body having two fuel passages connected in parallel through which fuel may pass simultaneously for admission to the engine, a valve for closing each passage, a piston connected with one valve and responsive to engine suction for closing the same, a spring for holding the other valve open, and temperature actuated means for controlling the actuation of said valves by the piston and spring in accordance with the ambient temperature.

4. In combination with an internal combustion engine, an automatic priming device comprising, a body having two fuel passages connected in parallel through which fuel may pass simultaneously for admission to the engine, a valve to close each passage, a piston connected with one valve and responsive to engine suction for closing said valve, a spring tending to hold the other valve open, and independent bi-metallic members anchored to said body and connected at their outer free ends with the valves for controlling the actuation of the valves by said piston and spring.

5. In combination with an internal combustion engine, an automatic priming device, comprising a body having two fuel passages connected in parallel, a valve for closing each passage, a piston responsive to engine suction for closing one of said valves, spring means for yieldably holding the other valve open, and bi-metallic U-shaped strips anchored to the body at one end and connected at their outer free ends with the valves for controlling the response thereof to said piston and spring respectively, the bi-metallic strip opposing the action of the piston holding its valve open by its inherent resiliency when the ambient temperature is low and until engine suction exceeds a predetermined degree and holding its valve closed regardless of variations in engine suction when the ambient temperature is high, and the bi-metallic strip of the other valve closing its valve against the action of the spring as the ambient temperature rises.

6. In combination with an internal combustion

engine, an automatic priming device comprising means providing two parallel fuel passages for conducting fuel from a common source to the engine, a valve in each of said passages for controlling the admission of fuel to the engine therethrough, engine suction operated means for regulating one of said valves, thermostatic means responsive to changes in the ambient temperature for opposing said engine suction operated means

whereby said valve is regulated jointly by engine suction and changes in the ambient temperature, means for nullifying any effect engine section might have on the other valve, and thermostatic means responsive to changes in the ambient temperature acting in conjunction with said last named means for regulating said other valve. 5
